UNITED STATES PATENT OFFICE.

FRANCIS M. F. CAZIN, OF HOBOKEN, NEW JERSEY.

ELECTRIC INCANDESCING LAMP.

SPECIFICATION forming part of Letters Patent No. 760,849, dated May 24, 1904.

Application filed September 1, 1903. Serial No. 171,515. (No model.)

To all whom it may concern:

Be it known that I, FRANCIS M. F. CAZIN, residing at Hoboken, in the county of Hudson and State of New Jersey, have invented certain new and useful Improvements in Electric Incandescing Lamps, of which the following is a specification.

My present invention relates to the class of electric incandescing lamps including a luminant embodying a non-electric and heat-conducting member carrying a primary and secondary conductor, the primary conductor being normally conductive, while the secondary conductor is normally non-conductive, or, in other words, the secondary conductor is conductive only at an elevated temperature.

A further object of my present invention is to provide a luminant of this character which is an improvement on the luminant disclosed in my copending application, filed October 2, 1899, Serial No. 732,399, which includes a secondary and primary conductor and which is automatically self-regulating to cut out or short-circuit the primary conductor when the secondary conductor has become conductive.

Again, my invention seeks to provide a luminant in which the primary conductor serves as a heater for the secondary conductor and support as well as to emit light and also to provide a supporting member which will readily and easily conduct the heat generated by the primary conductor to the secondary conductor to assist in maintaining it at its electric conducting temperature.

With other objects in view, which will be hereinafter apparent, the invention consists in the novel construction and combination of parts, all of which will be first described in detail and then specifically pointed out in the appended claims, reference being had to the accompanying drawings, in which—

Figure 1 is a side elevation, on an enlarged scale, of a luminant constructed in accordance with my invention. Fig. 2 is a vertical longitudinal section on the line 2 2 of Fig. 3. Fig. 3 is a similar view on the line 3 3 of Fig. 1. Fig. 4 is a top plan view of the parts shown in Fig. 1. Fig. 5 is a cross-section taken practically on the line 5 5 of Fig. 1.

Fig. 6 is a detail side elevation of a slightly-modified form of my invention. Fig. 7 is a top plan view thereof. Fig. 8 is a detail side elevation of my invention inclosed within a bulb as applied for use.

Referring now more particularly to the accompanying drawings, in which like numerals and letters of reference indicate like parts in all of the figures, 1 designates a suitable base of any approved construction and material, the material used being glass, porcelain, or other vitreous substance.

2 designates the non-current-conducting but heat conducting and distributing support, which may be either tubular, as shown in Figs. 1 to 5, inclusive, or it may be solid, as shown in Fig. 6, and the said support may be constructed of any material which possesses the proper strength which has a fusion-point sufficiently high to prevent the support becoming soft under the heat produced in the lamp, which while serving as an electrical and chemical insulator—*i. e.*, one which will serve as a non-conductor of electricity and which will be chemically neutral or non-active with respect to the material used in the primary and secondary conductors—will also serve to readily conduct the heat to the different points of the luminant.

The support 2 is mounted on or in the base 1, for instance, as shown in the drawings, by a glass seal 1^a, which will become an integral part of the base 1 and which will readily serve as an insulator between the leading-in wires 5 and the support. When the supporting-body 2 is hollow, I provide air-outlets 2^a 2^b to permit of the withdrawal of the air therefrom when the luminant is in position in the lamp-bulb and during the process of exhaustion.

The support 2 preferably has a pair of spirally-arranged grooves 2^b running the entire length thereof, which vary in their pitch according to the length of the primary conductor 3 it is desired to use, and these grooves 2^b are connected at the top of the support 95 by a transverse groove 2^c, so that the two grooves form in reality but a single continuous groove running around the luminant from bottom to top and then from top to bottom, as shown. In these grooves 2^b 2^b 2^c I wind a 100

primary conductor 3, which may be constructed of any approved material so long as the material used performs the desired functions of light and heat producing current conduction and which gives adequate resistance to the said current to produce the heat.

In the supplemental groove 2^d, which is of a less depth than the grooves 2^b 2^b, I place the secondary conductor 4, which is electrically connected at its ends, as at 4^a 4^a, through the terminals T to the leading-in wires 5 5 for a purpose presently explained, and the said secondary conductor is constructed of any material which may be of greater electrical resistance at normal temperature than the primary conductor, but which at a higher temperature will become more readily conductive than the primary conductor, whereby the secondary conductor will then serve to conduct the electric current and to maintain its required temperature and automatically cut out the primary conductor. Furthermore, the secondary conductor 4 is preferably constructed of such material as will emanate a great amount of light when under current and when heated to its required temperature.

While from practical experience I have found it unnecessary, yet, if desired, I may electrically insulate the primary and secondary conductors from each other and maintain electric connection or contact between them at the ends of the secondary conductor only, and when necessary I may interpose a chemically-neutral element or material between the secondary and primary conductors at the points of contact in any approved manner to act as a chemical insulator by preventing a chemical reaction taking place between the primary and secondary conductors at their points of contact.

The shape of the various parts is of but minor importance, the important features of the invention being in the combination, the relative position, and mainly the functions of the specifically-located parts.

The terminals T between the primary and secondary conductors and the leading-in wires may be made of any suitable material which will perform the following functions, to wit: the passive function of being supported inside of the parts which protect the luminant, the active function of protecting the juncture between the leading-in wires, which are of comparatively low electrical resistance and the primary conductor of comparatively high electrical resistance, the active function of not alone passing the electric current through the leading-in wires and the light and heat producing primary conductor, but also of obviating local detrimental resistance and consequent heat accumulation, and the active function of preventing mutual chemical reaction under electric current between the leading-in wires and the primary and secondary conductors or any other part of the luminant

and of dismissing, by means of porosity, the gaseous product of unavoidable chemical reaction or admission of air or gas in preventing detrimental reaction.

In Figs. 6 and 7 I have shown a slightly-modified form of my invention in which I use a plurality of secondary grooves 2^d to receive a plurality of secondary conductors, which are preferably joined in multiple, as at 4^c, and which are electrically connected to the leading-in wires 5 5, and the said multiple secondary conductors perform the same functions as those shown in Fig. 1. I desire it understood that I may vary the number of secondary conductors as occasion may demand and experience prove desirable, and I do not desire to limit myself to the exact details of construction, combination, and arrangement of parts, as slight changes in the detail arrangement and construction of parts may be made without departing from the scope of my invention.

While I may construct the primary conductors of metal or of carbon or of suitable alloy or combination of metals or other suitable substance, yet I desire it specially understood that I may employ any substances whatsoever which will fulfil the desired and necessary functional requirements, such as mechanical strength and current resistance, and which will emanate heat under adequate current, &c.

Again, while I may use the oxids of the rare metals or of the rare metals in combination with other substances, yet I may use any substances whatsoever which will perform the desired function of being normally non-conducting and which will conduct at high temperatures, which will at such high temperatures be of less electrical resistance than the primary conductor, and which when heated will incandesce to produce light. Furthermore, while I prefer to use a porcelain or kaolin support on the glass or other base, yet I may use any substance which will serve the intended purposes of the support—namely, such substances as are chemically neutral, electrically non-conducting, and such as are conductors of heat. When a support which is not chemically neutral or electrically non-conductive is used as a support, I may provide any suitable chemical or electric insulation, or both, between the said support and the remaining parts.

So far as described the operation of my invention may be best explained as follows: The current is turned onto the leading-in wires. It then transverses the primary conductor, causing it to become heated and in turn heat the supporting element and the adjacent parts of the secondary conductor, the remaining portions of the secondary conductor becoming heated from the heat conducted by the support to such portions. As soon as the secondary conductor has become sufficiently heated to become electrically conducting—i. e., its re-

sistance reduced to less than that of the primary conductor—the said secondary conductor will then serve as the primary conductor to conduct the main portion, if not all, of the 5 electric current used in the luminant, which then serves to further heat the secondary conductor (now primary) until it becomes incandescent to emanate light.

From the foregoing description, taken in 10 connection with the accompanying drawings, it is thought the advantages and complete operation of my invention will be readily apparent to those skilled in the art to which it appertains.

15 Having thus described my invention, what I claim, and desire to secure by Letters Patent, is—

1. In a luminant for electric incandescent lamps, a heat-conducting support, a heat-producing primary electric conductor carried thereby, a normally non-conducting secondary conductor mounted on said support and in electrical contact with said primary conductor, as specified.

25 2. In a luminant for electric incandescent lamps, a heat-conducting support, a heat-producing primary electric conductor carried thereby, a normally non-conducting secondary conductor mounted on said support and in electrical contact with said primary conductor, as specified.

30 3. In a luminant for electric incandescent lamps, a heat-conducting support, a heat-producing primary electric conductor carried thereby, a normally non-conducting secondary conductor mounted on said support and in electrical contact with said primary conductor, as specified.

35 4. In a luminant for electric incandescent lamps, a heat-conducting support, a heat-producing primary electric conductor carried thereby, a normally non-conducting secondary conductor mounted on said support and in electrical contact with said primary conductor, said secondary conductor adapted to conduct electricity at an elevated temperature, as specified.

40 5. In a luminant for electric incandescent lamps, a heat-conducting support, a heat-producing primary conductor carried thereby, a normally non-conducting secondary conductor mounted on said support and in electrical contact with said primary conductor, said secondary conductor adapted to conduct electricity and short-circuit the primary conductor when heated to an elevated temperature.

45 6. In a luminant for electric incandescent lamps, a heat-conducting support, a heat-producing primary conductor wound thereon, a normally non-conducting element mounted on said support and adapted to receive heat from the primary conductor and the support, for the 50 purposes specified.

55 7. In a luminant for electric incandescent lamps, a heat-conducting support, a heat-producing primary conductor wound thereon, a normally non-conducting element mounted on said support and adapted to receive heat from the primary conductor and the support, so as to become conductive to cut out the primary conductor and to become incandescent.

60 8. In a luminant for electric incandescent lamps, a dielectric supporting heat-conducting part having spiral grooves, a heat-producing primary conductor wound in said grooves, a light-producing member mounted over said primary conductor on the supporting part, said light-producing part adapted to receive

heat from the support and to become incandescent and conductive at an elevated temperature to cut out the primary conductor, as specified.

7. In a luminant for electric incandescent lamps, a dielectric supporting and heat-conducting part having spiral grooves and longitudinal grooves, a primary heat-producing current-resisting conductor wound in said spiral grooves of said support and adapted, 75 under current, to heat said support, a light-producing normally non-conducting member held in said longitudinal grooves with its ends in electric contact with the primary conductor and adapted to become heated and made conductive by the heat produced in the luminant and to short-circuit the primary conductor at predetermined times, and adapted to emanate light, for the purposes specified.

8. In a luminant for electric incandescent 85 lamps, a dielectric heat-conducting support, a heat-producing primary conductor wound thereon, a light-producing normally non-conducting filament carried by said support, said heat-producing conductor adapted to heat said support, and said support and conductor adapted to heat said light-producing filament whereby it becomes conductive, for the purposes specified.

9. In a luminant for electric incandescent 95 lamps, a dielectric heat-conducting support, a heat-producing primary conductor wound thereon, a light-producing normally non-conducting filament carried by said support, said heat-producing conductor adapted to heat said 100 support, and said support and conductor adapted to heat said light-producing filament whereby it becomes conductive, and short-circuits the heat-producing conductor, for the purposes specified.

10. In a luminant for electric incandescent lamps, a dielectric heat-conducting support, a heating-coil wound thereon, a light-producing filament or thread also mounted on said support, said filament being of greater electrical resistance at normal temperature than the heating-coil, and of less electrical resistance at high temperature than said coil to permit said filament to become conductive and incandescent at an elevated temperature and 110 automatically cut out said heating-coil.

11. In a luminant for electric incandescent lamps, a dielectric heat-conducting support, a heating-coil wound thereon, a light-producing filament or thread of rare metal oxides 120 also mounted on said support, said filament being of greater electrical resistance at normal temperature than the heating-coil and of less electrical resistance at high temperature than the said heating-coil to permit said filament becoming conductive and incandescent at said elevated temperature and automatically short-circuit said heating-coil, as specified.

12. In a luminant for electric incandescent 130 lamps, a dielectric heat-conducting supporting

part, a heating-coil wound thereon, and adapted to heat said support when under current, a light-producing filament or thread mounted on said support, said filament being composed of material which will offer a greater electrical resistance to the current at normal temperature than the heating-coil and which at the elevated temperature produced by said heating-coil, will become of less electrical resistance than said heating-coil to permit the current being shunted through said filament to raise it to incandescence, for the purposes specified.

13. In a luminant part of electric incandescent lamps, a dielectric heating and conducting support, a heating-coil wound on said support, adapted to heat said support when under current, light-producing filaments mounted on said support having their ends in electrical contact with said heating-coil, said light-producing filament being of higher electrical resistance at normal temperature than the heating-coil, and of less electrical resistance at an elevated temperature than the heating-coil whereby said light-producing filament will pass the current when at an elevated temperature to raise the filament to incandescence, said heating-coil having portions exposed, for the purposes specified.

14. In a luminant part of electric incandescent lamps, a dielectric heat-conducting support, a heating-coil wound on said support, adapted to heat said support when under current, light-producing filaments mounted on said support having their ends in electrical contact with said heating-coil, said light-pro-

ducing element being of higher electrical resistance at normal temperature than the heating-coil, and of less electrical resistance at an elevated temperature than the heating-coil whereby said light-producing element will pass the current when at an elevated temperature to raise said element to incandescence, said heating-coil having exposed portions to serve as auxiliary light-producing parts.

15. In a luminant for electric incandescent lamps, a heat-conducting support, a heat-producing primary conductor carried thereby, a normally non-conducting second conductor carried by said support, terminals mounted on the support for connecting the primary and second conductors, said terminals being of sufficient conductivity to prevent local resistance and heat accumulation.

16. A luminant for electric incandescent lamps, comprising a heat-conducting support, a heat-producing primary conductor carried thereby, a normally non-conducting second conductor also carried by said support in electrical contact with said primary conductor, leading-in wires for said primary and secondary conductors, and terminals carried by said support for connecting said primary and secondary conductors to said leading-in wires, said terminals being of sufficient conductivity to prevent heat accumulation at the juncture of the said primary and secondary conductors and the leading-in wires.
